CLAIM

The ornamental design for an anatomical teaching model, as shown and described.

DESCRIPTION

FIG. 1 is a perspective view of an anatomical teaching model.

FIG. 2 is a right side view of the anatomical teaching model.

FIG. 3 is a left side view of the anatomical teaching model.

FIG. 4 is a top side view of the anatomical teaching model.

FIG. 5 is a bottom side view of the anatomical teaching model.

FIG. 6 is a front side view of the anatomical teaching model; and,

FIG. 7 is a back side view of the anatomical teaching model. The broken lines are directed to environment and are for illustrative purposes only. The broken lines form no part of the claimed design.
